his Attorney.

UNITED STATES PATENT OFFICE.

OSCAR J. OLM, OF MINNEAPOLIS, MINNESOTA, ASSIGNOR TO NORTHWESTERN PAPER GOODS CO., OF ST. PAUL, MINNESOTA, A CORPORATION OF MINNESOTA.

ENVELOPE.

Application filed September 6, 1921. Serial No. 498,750.

My invention relates to an envelope which is adapted to receive matter which is subject to different postal rates and is so constructed as to form a single envelope with 5 separate compartments. The compartments of the envelope can be closed separately from each other so that first class matter may be carried in one compartment and other matter carried in another compartment which is 10 subject to a different postal rate.

It is a feature of the invention to provide an envelope of a very simple construction so that it can be manufactured for practically the same cost as the ordinary one compartment envelope. This is accomplished by 15 making the body of the envelope out of a single piece of material which forms a very important part of this invention. It is essential in an envelope of this character which 20 is adapted to carry matter requiring different postal rates to provide an envelope which will be accepted by the postal department with assurance that the compartments will not separate from each other and which is 25 of a construction of the same compactness as the ordinary envelope. This is particularly true in sending automobile licenses through the mail. Obviously, this invention is different from other envelopes which are 30 designed to accomplish this purpose and which consist of two separate complete envelopes. Such inventions are expensive to manufacture and are apt to separate which makes a distinct disadvantage in such a construction. 35 By forming my envelope out of one single piece of material, the same is folded and glued in a manner to form separate compartments, thus requiring practically no more labor than the making of the ordinary envelope but a very little more material. 40

Another feature of the invention is the closing flaps for the different compartments which are arranged adjacent each other which allows the easy insertion of matter 45 into the different compartments of the envelope.

In the drawings forming part of this specification:

Figure 1 is a front elevation of my envelope with the closing flaps in open position. 50

Figure 2 is a section on the line 2-2 of

Figure 1 showing the flaps in closed position.

Figure 3 is a section of the line 3-3 of 55 Figure 1.

Figure 4 illustrates a geometrical development of the envelope as it is blanked out from a single piece of material.

Figure 5 illustrates an alternative geomet- 60 rical development of my envelope.

In the drawings, the envelope A is of a rectangular shape having a body portion 10 which is formed from a single piece of material and is blanked out as illustrated in 65 Figures 4 and 5.

The body portion 10 is formed with a back portion 11 from which extend portions 12 and 13 along one side while the portion 14 extends from the opposite side thereof. 70

The closing flap 15 is formed extending from one end of the back 11 and a short flap 15' projects from the opposite end of the body portion.

The portion 13 is adapted to be folded 75 over onto the portion 12 along the line 16. The member 14 is folded over onto the member 11 along the line 17 and then the portions 12 and 13 are folded over onto the portion 11 along the line 18 and adapted to 80 overlap the edge 19 of the portion 14 to which they are glued. The end flap 15' is then folded over on the line 20 and secured by gluing to the overlapping portions 12 and 14. In this manner the portion 13 is entirely enclosed beneath the portions 12 and 85 14 and the back 11 and forms one side of the separate compartment B extending from one end to the other of the envelope while the back 11 and the portions 12 and 14 form the 90 main compartment C. The compartment B is considerably smaller than the compartment C but both compartments extend in the same longitudinal direction of the envelope. 95

The portion 13 is formed with a closure flap 22 which has the ordinary glue surface so that the flap 22 can be secured to close the compartment B. The portion 12 can be formed with the ordinary envelope window opening 23 so as to disclose the address written on the article adapted to be enclosed in the compartment B from the outside of the envelope. The compartment B is particularly adapted to carry first class mail matter 100 105

and when the flap 22 is secured the contents of the compartment B is enclosed as required for first class mail matter.

The compartment C is provided with the enclosing flap 15 adjacent to the enclosing flap 22 and at the same end of the envelope A but this flap does not have any glue or any means for permanently gluing the same but can be inserted between the sides forming the compartment C or held closed in any other suitable manner. The contents of the compartment C must be readily accessible to the postal authorities so that the same can be inspected whenever it is desired. In this manner the envelope A can carry in the compartment C such matter as requires a lower postal rate than the matter carried in the compartment B.

The invention includes the essential features of making the envelope A in a certain manner. This is accomplished primarily by the portion 13 which is folded on the line 16 onto the portion 12 and in turn both 12 and 13 while folded together are folded over onto and secured to the edge of the portion 14 and adjacent to the portion 11. This construction of envelope is very simple to make. It does not require but a very little more labor than the ordinary envelope and the only extra material is that which is required to make the portion 13. This construction provides a very flat or compact receptacle or envelope in which separate compartments are arranged. Envelope A is formed from the sheet material 10 by four distinct folds of the same, the first fold being along the line 17, the second along the line 16 and then along the line 18 after which the short flap 16 is folded over along the line 20, thus in the construction of this envelope there is only one more fold than in the ordinary envelope, in making up the body of the same.

In Figure 5 the alternative geometrical development of my envelope illustrates the portion 13 of approximately half the length as it is illustrated in Figure 4. In this construction the portion 13 is provided with a tongue or flap 24 which is glued to the portion 12 when the portion 13 is folded over onto the same. In forming up this construction of my envelope the length of the compartment B would be considerably shorter than that illustrated by the geometrical development of the same in Figure 4. In this form of my envelope less material would be required to make the member 13, and where only a small compartment B is required this construction is very adaptable.

Simplicity of construction is of primary importance in my envelope and it is obvious that the compartments B and C are securely attached together so that it would be practically impossible for them to be separated during ordinary use in the mails.

Further, the fact that my mail enclosure is formed from a single piece of material makes it more easy to form a practical device and the easy folding of the same will be readily apparent. These details go together to make up a mailing envelope which is adapted to certain purposes, where an envelope with several separate compartments is desired.

I have endeavored to illustrate in the drawing the simplest development of my envelope and I desire to have it understood that I do not wish to confine my invention to the exact form shown but wish to protect the same within the scope of the following claims.

I claim—

1. A two compartment envelope formed from a single piece of material, a body portion adapted to form one wall of one of the compartments of said envelope, long and short flaps extending from oppositely disposed sides of said body portion, said long flap being folded to form a second compartment, an address window formed in one of said flaps, a single flap for covering one end of both of the compartments of said envelope, and independent flaps for closing each of the compartments of said envelope.

2. An envelope formed from a piece of sheet material, including a back portion, a portion extending from one side of said back portion adapted to form a part of the front of said envelope and a second portion extending from the other side of said envelope adapted to form the other part of the front of said envelope, said second portion being folded on itself in a manner to form a compartment in the front of said envelope which is separate from the main compartment formed by the front and back walls of said envelope and a closure flap for each of the said compartments of said envelope.

3. An envelope including a main compartment and a secondary compartment formed from a single piece of material, one wall of said main compartment being formed by a single sheet of material, flaps extending from said wall, one of said flaps being folded over on to itself to form the secondary compartment, said folded-over flap being united with the flap extending from the opposite side of said wall of said envelope to form the other wall of said envelope, an end flap for uniting the folded-over flaps to close one end of the main compartment, and separate closure flaps for said main and secondary compartment.

4. An envelope, including a compartment formed with front and back walls, said front wall including a long and a short flap, the long flap being folded on itself to form the walls of a separate compartment and said long and short flaps being secured together

to form the front wall of said compartment, thereof some of which are adapted to be 10 folded to form a receptacle which in turn functions as a portion of one wall of another receptacle; another of said extensions adapted to be folded to complete the said unfinished wall of the other receptacle; and 15 means to seal the ends of said receptacles.

5. In a mail container of the class described, consisting of a single sheet of material having extensions from the main body
